UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,155,643.

Specification of Letters Patent.

Patented Oct. 5, 1915.

Application filed May 6, 1911. Serial No. 625,517.

To all whom it may concern:

Be it known that I, JOHN L. CREVELING, a resident of New York, in the county and State of New York, have invented certain new and useful Improvements in Electric Regulation, as set forth in the annexed specification and drawing, forming a part thereof.

My invention pertains to that class of electric regulation wherein a dynamo or generator is automatically governed under varying conditions and has for its particular object to provide means whereby certain fluctuations in the output apt to take place in such automatic systems may be avoided.

The drawing illustrates one type of system embodying the essentials of my invention.

In said drawing 1 represents a dynamo or generator provided with the usual field coil 2 and from which the positive lead 3 is carried to the positive side of the storage battery 4 and lamps or other translating devices 5. The negative terminals of the translating devices are carried to the lead 6 in communication with the negative side of the storage battery 4 and connected with the negative brush of the generator through solenoids 7 and 8, the functions of which will hereinafter appear. The field 2 is governed by the carbon pile 9 which is controlled as by the lever 10 normally drawn upwardly by the adjustable spring 11 in such manner as to compact the carbons 9 and 35 reduce the resistance thereof. The lever 10 is provided at one extremity with a magnetic core 12 so disposed as regards the solenoid 8 that its excitation tends to draw the core downwardly and increase the resistance 40 9. The solenoid 13 is preferably of fine wire and has one terminal connected to the lead 6 and is wound in such direction as to assist the solenoid 8, and the opposite terminal is connected as by wire 14 with the conducting segment 15 in electrical communication with the lever 16 normally resting upon the blank segment 17 of the variable resistance device 18, having one terminal connected as by wire 19 with the lead 3.

50 20 is a ratchet carried upon the shaft 21 which shaft also carries the lever 22 normally drawn in an upward direction against the stop-screw 24. The lever 22 is provided at one extremity with the core 25 so disposed with regards the solenoid 7 that excitation

of the same tends to draw the core downwardly against the action of spring 23. The lever 22 is provided with an extension carrying a pivot 27 upon which is placed the pawl 26 attached to the arm 28 provided at its extremity with the weight or ball 29 normally drawn upwardly as by the adjustable spring 30 against the adjustable stop 31. The levers 10 and 22 may be provided with dash-pots 32 so as to resist too sudden movement.

The operation of my invention is substantially as follows: Starting with the various instrumentalities in the positions indicated in the drawing and the generator running at such speed and its voltage such as to cause it to have substantially no output and at the same time substantially no back discharge from the battery, then no appreciable current will be flowing to or from the generator. If the speed be increased, however, current will flow from the generator to the battery and translating devices until the maximum current is reached and then by properly adjusting the spring 11, the solenoid 8 may be caused to draw the core 12 downwardly so as to increase the resistance 9 and prevent any further rise in voltage upon increase in speed of the generator. The current rising gradually from zero to its desired maximum will cause the core 25 to be drawn downwardly by the solenoid 7 against the action of spring 23 if the same be properly adjusted, and the pawl 26 will move around the periphery of the ratchet 20 without engaging the teeth thereof, and the ratchet, therefore, will receive no motion and will remain in the position shown in the drawing and the lever 16 will remain upon the blank segment 17 and there will be no current through the solenoid 13. If, however, sudden changes in load take place as, for example, should the belt driving the generator slip and cause the output to vary rapidly from little to a considerable output, as such intermittent slipping, which is apt to take place in this type of system, will cause the speed of the generator to rise and fall very rapidly and thus cause the output thereof to surge, the core 25 would be drawn upwardly and downwardly with considerable rapidity and the inertia of the ball 29 will cause the pawl 26 to be thrown into engagement with the ratchet 21 in a well-known manner and pulsations of the core 25

with the pawl 26 thus engaging the ratchet will move the lever 16 in a left-handed direction in such manner as to cut in the solenoid 13 through a high resistance and then 5 gradually decrease the same as long as the pulsation continues. This cutting in of the solenoid 13 and increasing of the strength thereof cuts down the current necessary in the coil 8 in order to overcome the spring 11 10 and, therefore, the total generator output for which this regulator is adjusted is lessened and the load upon the generator therefore lessened. This lessening of the load will overcome the slipping of the belt and when 15 this point is reached there will be no more pulsating of the core 25 and the resistance 18 then in circuit will remain unaltered unless further slipping and surging take place. This adjustment will remain until the belt 20 is properly tightened and then the lever 16 may be reset to the position shown in the drawing.

I do not wish in any way to limit myself to the exact details of construction or exact 25 mode of operation set forth in the accompanying drawing and specification which are given merely to illustrate one type of system embodying the essentials of my invention which is as set forth in the following 30 claims.

I claim—

1. The combination of a generator, automatic regulating means therefor, and means for producing additional effects in the operation of said regulating means only upon 35 intermittent effects in the performance of the generator.
2. The combination of a generator, automatic means for regulating the same, and means for additionally affecting the regulating means only in response to intermittent abnormal operation of the generator.
3. The combination of a generator, automatic means for controlling the same, electromagnetic means for operating said controlling means, and means for additionally affecting the controlling means only in response to fluctuations in the generator output.
4. The combination with a generator having 50 a field circuit, of automatic means for controlling said field circuit, means for operating said controlling means in response

to fluctuations in current output, and means for affecting said controlling means affected 55 by alterations in generator current.

5. The combination with a generator and an automatic regulator therefor, of means for adjusting the operation of said regulator to increase the effect thereof depending only 60 upon intermittent fluctuations in generator output.

6. The combination of a generator and automatic means for regulating its output, with automatic means for limiting the output 65 operated in response only to intermittent action of the generator.

7. The combination with a generator, of means for regulating the same and means for adjusting the regulating means only in response 70 to sudden surging in generator output.

8. The combination with a generator and automatic means for regulating the same, of electromagnetic means for affecting the 75 regulating means and electromagnetic means controlling the first named electromagnetic means in response only to intermittent fluctuations in generator output.

9. The combination with a generator and 80 a regulator therefor, of electromagnetic means affecting said regulator and electromagnetic means for altering the current therein in response only to intermittent variations in generator output.

85 10. The combination with a generator and a regulator therefor responsive to current fluctuations, a coil affecting said regulator, means for controlling the action of said coil comprehending a rheostat and electromagnetic means for operating the same responsive to intermittent variations in generator output.

90 11. The combination with a generator, a regulator therefor including means for operating the regulator, other means for affecting the operation of the regulator to increase the effect thereof, and means for causing the second-named operating means to become active only upon the occurrence of 100 rapid fluctuations in the generator output.

JOHN L. CREVELING.
